UNITED STATES PATENT OFFICE.

CHARLES ISAAC ADAMS, OF LONDON, ENGLAND.

INTERNAL-COMBUSTION ENGINE.

1,306,939.

Specification of Letters Patent. Patented June 17, 1919.

Application filed November 9, 1917. Serial No. 201,022.

To all whom it may concern:

Be it known that I, CHARLES ISAAC ADAMS, a subject of the King of Great Britain, residing in 24 Beverley road, Chiswick, W.4, 5 London, England, have invented certain new and useful Improvements in Internal-Combustion Engines, of which the following is a specification.

This invention relates to rotary engines and it refers to engines of the type in which a number of radially disposed cylinders, arranged to operate upon the Otto four-cycle principle, are carried upon a rotary body forming the engine flywheel.

The present invention has for its object certain improvements in engines of the above type whereby in order to increase the efficiency of the engine by increasing the number of strokes for each revolution, the piston speed is increased so that a greater number of explosions per revolution may be obtained.

In accordance with this invention the connecting rods of each piston are connected to an intermittently rotating body or crank, the movement of which is controlled by a suitable cam or cams the arrangement being such that the piston speed is considerably accelerated whereby the number of strokes completed by each piston per revolution of the engine may be increased. With the bulk of engines of this class as at present constructed, owing to the type of construction a low piston speed is obtained, it is only possible to secure two strokes per revolution of the engine.

In order that the invention may be the better understood drawings are appended in which:—

Figure 1 is a diagrammatic view showing the action of the cranks and of the connecting rods.

Fig. 2 is a similar view illustrating an arrangement of the cranks and the cam operating said cranks.

Fig. 3 is a sectional view of an engine embodying the present invention.

Fig. 4 is a front view of said engine.

Fig. 5 is a sectional view showing the arrangement whereby fuel is supplied to the cylinders.

Referring to Fig. 1 of the accompanying drawings in which for the sake of clearness the action of a single cylinder only is shown.

In the said figure, 1 indicates the fixed shaft of the engine, and 2 the intermittently

moving disk or crank. 2^c indicates the rod connected to the crank and to the piston, not shown. In Fig. 1 it is assumed that the piston is at the commencement of the firing stroke when the parts would occupy the position shown. The motion of the crank, the speed of which is somewhat higher than the speed at which the cylinders move, is intermittent, the arrangement being such that the crank case and with it the cylinders carried thereby are moved through an angle of 90° while the crank itself moves through an angle of 180°. By this means the piston speed is considerably accelerated.

The desired movement of the crank 2 is in the present instance secured by means of the parts shown in Fig. 2 in which is illustrated an arrangement designed for use with a four cylinder engine. In the figure referred to 4 indicates a cam path which is fixed relatively to the cylinders, 5 indicates the crank casing to which the said cylinders are attached. Pivottally connected to the arms 2^a, are links 7 and 8 carrying at their outer ends rollers which engage the aforesaid cam path 4. The rollers upon the links 7 and 8 are carried by slippers or equivalent means working in guides 7^a, 8^a supported from and moving with the crank case 5. The outline of the cam path 4 is such that the crank is intermittently moved in the same direction as the case 5. Connected to each of the pins forming the pivots of the arms 2^a, 2^b are two connecting rods 2^c which in turn are connected to the respective pistons in the four cylinders.

Referring to the engine shown in Figs. 3 and 4 as in Figs. 1 and 2, 1 indicates the shaft upon which are revolvably mounted two double cranks indicated respectively by 2 and 9. Connected to the arms of crank 2 are the links 7 and 8 which links carry pins with rollers at either end, running in the cam paths 4 and with which links are associated other rollers 10, 11 preferably mounted on ball bearings and running in the guides 7^a, 8^a. Connected to the crank pins 12, 13 are the inner ends of rods 2^c which rods at their outer ends are connected to the piston 14 moving in cylinders 15 which cylinders are mounted upon and revolve with the crank case 5. The cam path 4 is formed upon a disk or plate *w* which is disposed in the crank case and which disk is secured in any suitable manner to the shaft 110. 16, 17 indicate respectively the admission

cranks, rollers engaging said cams, guides for said rollers, said guides moving with the crank case, links to which said rollers are attached, said links being connected to the cranks, the cams being of such outline that the cranks are intermittently actuated and the speed of the pistons for certain strokes is accelerated, admission and exhaust valves for the cylinders, spring 5 pressed valves for said admission and exhaust, levers operating the valves, rods operating said levers, a second lever for the

valve rods said levers being operated by cams upon the engine casing, passages upon the side walls of the crank casing, and passages in the engine shaft and upon the wall of said crank casing for the passage of fuel to the cylinders. 15

In testimony whereof I affix my signature in the presence of two witnesses.

CHARLES ISAAC ADAMS.
